CURLER

Abraham Goodman, New York, N. Y., assignor to
Delamere Company, Inc., a corporation of
Delaware

Application February 24, 1934, Serial No. 712,695

1 Claim. (Cl. 132—41)

This invention relates to a hair curler, and more particularly to improvements in a curler having a form or mandrel on which the hair is wound. With this type of curler the hair is wound tightly around the form, the latter being retained in the hair until the curl is set. It is usual to wet the hair when forming the curls and to leave the device in the hair for a considerable length of time until the hair is thoroughly dried.

10 In the use of such a curler, it is impossible to insert a hair pin in the curl while the device is in the hair. After the device is withdrawn, it would also be impossible to insert a pin because the mere insertion of a pin in the curl would dis-

15 arrange and distort the curl.

An object of the present invention is to provide a curler of the winding type, having a longitudinal recess for insertion of a hair pin in the curl while the hair is wound on the curler, so that the curl may be fastened immediately upon its forming and securely held in shape after the removal of the curler.

My device provides means whereby curls may be formed and held in place instantaneously, thus greatly facilitating the dressing of the hair. Furthermore, the device permits of forming curls and pinning them tightly to the scalp.

Another advantage of the invention is that the curls may be formed expeditiously while the hair is dry and without the necessity of dampening the hair with water or hair-waving lotion.

With these and other objects in view, the invention consists in the novel features of construction and arrangement of parts hereinafter described, it being understood that modifications may be made therein without departing from the spirit and scope of the invention as defined in the claims.

The accompanying drawings illustrate a preferred embodiment of the invention, in which:—

Figure 1 is a side elevation of the curler with the clasp in locked position;

Fig. 2 is a side view with the clasp unlocked, showing, in dotted lines, one of the fingers in open position;

Fig. 3 is a cross-section, on an enlarged scale, taken on the line 3—3 of Figure 1;

Fig. 4 is a similar view showing a lock of hair wound thereon;

Fig. 5 is a side view of a conventional hair pin of the "bobble" type;

Fig. 6 is a side view showing the ends of the hair gripped between the fingers of the device;

Fig. 7 is a side view showing the hair wound on the device;

Fig. 8 is a similar view with the clasp in locked position;

Fig. 9 is a rear side view showing a hair pin inserted in the curl while the latter is wound around the device; and

Fig. 10 is a perspective view of the formed and pinned curl after the device has been removed therefrom.

The device, in the form illustrated, comprises two finger members 1 and 2, said members being pivoted together at 3 and having handle portions 4 and 5. A spring 6, indicated by dotted lines in Figure 1, serves to urge said finger members together. A clasp member 7 may be provided for temporarily retaining the device in the hair. This clasp member may consist of an elastic cord or band, as shown, or it may be of any other suitable construction.

An essential feature of the invention consists in so forming the finger members, that, when closed, a longitudinal recess 8 is formed, which recess permits of the insertion of a "bobble" pin so as to pin the curl while it is in place on the device.

In the particular form of device illustrated, the fingers 1 and 2 are hollow and circular in cross-section, so that when they come together, as shown in Fig. 3, a recess 8 is formed on each side between the opposed portions of the two fingers. It is to be understood that the invention is not limited to fingers of circular cross-section as other forms of fingers may be used, the essential feature being that a recess is formed and to this end the fingers may be of any form so that they are laterally contracted towards the plane of their bearing on one another. Furthermore, the fingers may be either of hollow or solid construction, as desired.

In Fig. 5 I have illustrated a bobble pin 9 for use in the practice of the invention. The pin here shown is of the type having straight legs, but any other form of bobble pin may be used.

In using the device, the ends of the hair are gripped between the two fingers as shown in Fig. 6 and the device is then rotated to wind the hair in a curl around the fingers, after which the clasp 7 is locked so as to hold the device in the hair temporarily and to leave both hands free to insert the hair pin. The legs of the pin are then spread and one leg is inserted in the recess 8 under the curl, while the other leg extends over the curl, thus holding the curl in its position. The clasp is then unlocked and the device removed from the hair, leaving a perfectly formed, tightly pinned curl.

It will be seen that the device permits of winding the curl and pinning it as close to the scalp as may be desired, and, obviously, that more than one pin may be used in the curl, if so desired.

5 What I claim is:—

A hair device of the character described, comprising a pair of pivotally connected spring tensioned fingers between which the ends of a wisp of hair are adapted to be gripped and about 10 which the hair is adapted to be wound in a curl so as to encompass both of the fingers, said fingers having substantially similar portions on op-

posite sides thereof which extend longitudinally thereof and in substantial register with the pivotal point to provide a pair of opposite recesses between said portions of the fingers whereby to enable one leg of a hair pin to be inserted in either of the recesses and engaged with the parts of the wisp that extend transversely across the recesses so that upon withdrawal of the fingers the curl will be retained by the hair pin, and means to hold the wisp in curled form during 10 positioning of the hair pin.

ABRAHAM GOODMAN.
